UNITED STATES PATENT OFFICE

ERWIN HOFFA AND CARL SEIB, OF FRANKFORT-ON-THE-MAIN-HOCHST, GERMANY,
ASSIGNORS TO GENERAL ANILINE WORKS, INC., OF NEW YORK, N. Y., A CORPORATION OF DELAWARE

PROCESS OF PRODUCING AZO DYESTUFFS ON THE FIBER

No Drawing. Application filed June 5, 1928, Serial No. 283,126, and in Germany June 13, 1927.

Our present invention relates to a process of producing azo dyestuffs on the fiber.

It is based on the discovery that diazonium borofluorides as well as tetraazonium borofluorides of amines of the aromatic series, including those which already possess dyestuff character, are extremely suitable for producing dyestuffs on the fiber and that dyeings of very good properties of fastness are obtained by dyeing or printing by means of the said diazonium compounds on vegetable or animal fibers which have been pre-treated with any coupling component, for instance a naphthol or a body of similar action, such as 2:3-hydroxynaphthoic acid arylides, pyrazolones, dipyrazolones, acetoacetic (acid) arylides or diacetoacetic (acid) diaminodiarlyl compounds. The dyeings thus obtained are in many cases distinguished by a particular brilliancy in comparison with those which are produced by means of the usual diazo solutions.

The following examples illustrate the invention, it being understood that they are in no way limitative:

Example 1.—Example for the production of the dyestuff from 2:3-hydroxynaphthoic acid-2'-methyl-1'-anilide and phenyldiazonium borofluoride when the material is dyed in lots of 25 kilos, treated with a grounding liquor in the open vat and subsequently dyed in the tureen.

There is first prepared in a vat holding 500 liters a grounding bath containing 7:5 grams of 2:3-hydroxynaphthoic acid-2'-methyl-1'-anilide per liter and composed as follows:

3.75 kilos of 2:3-hydroxynaphthoic acid-2'-methyl-1'-anilide
7.5 liters of Turkey red oil of 50 per cent. strength
5.7 liters of caustic soda solution of 34° Bé.
40 3.75 liters of formaldehyde of 33 per cent. strength;
made up to
500 liters of liquor.

To this bath is subsequently added for 25 kilos of material to be dyed, 0.375 kilos of 2:3-hydroxynaphthoic acid-2'-methyl-1'-anilide. The yarns are treated with the grounding liquor for 1/2 hour and freed from water by hydro-extraction.

For the development of the dyestuff there is used a chassis holding 30 liters of liquor,

which contains 3.85 grams of phenyldiazonium borofluoride per liter.

There is first prepared a bath with

115.5	grams of phenyldiazonium borofluoride
1.5	kilos of sodium chloride
0.02	liters of acetic acid of 50 per cent. strength, made up to
30	liters of liquor.

To this bath is subsequently added for 26 kilos of material to be dyed, 0.300 kilos of phenyldiazonium borofluoride contained in 12.5 liters of liquor composed as follows:

300	grams of phenyldiazonium borofluoride
0.5	kilo of sodium chloride
0.08	liters of acetic acid of 50 per cent. strength, made up to
12.5	liters of liquor.

The grounded yarns are once passed through the bath in hanks of 1 kilo. For every 1 kilo of yarn, 1/2 liter of additional liquor is to be added. After the development is complete, the material is rinsed several times and soaped at a temperature of about 60° C. for 1/2 hour with 2 grams of soap per liter, finally it is rinsed and dried. In this manner a vivid reddish-orange tint is obtained which is much clearer than that of the dyeing obtainable by using the phenyldiazonium chloride. The dyestuff has the following formula:

Example 2.—There is first prepared in a vat holding 500 liters a grounding bath containing 5 grams of 2:3-hydroxynaphthoic acid-4'-chloro-2'-methyl-1'-anilide per liter, the bath being composed of

2.5 kilos of 2:3-hydroxynaphthoic acid-4'-chloro-2'-methyl-1'-anilide
5 liters of Turkey red oil of 50 per cent. strength
5 liters of caustic soda solution of 34° Bé.
2.5 liters of formaldehyde of 33 per cent. strength;
made up to
500 liters.

To this bath is subsequently added for 25 kilos of material to be dyed 0.5 kilo of 2:3-hydroxynaphthoic acid-4'-chloro-2'-methyl-1'-anilide. The yarn is then ground with this liquor for 1/2 hour and freed from water by hydro-extraction.

For the development of the dyestuff is used: First a bath prepared as indicated in Example 1, but instead of 115.5 grams of phenyldiazonium borofluoride 144 grams of 4-chloro-2-methyl-1-phenyldiazonium borofluoride are used.

Into this bath are subsequently introduced 376 grams of 4-chloro-2-methyl-1-phenyldiazonium borofluoride instead of 300 grams used in Example 1.

The method of working being the same as that in Example 1, a vivid bluish-red is obtained. The dyestuff has the following formula:

13

20

By using 5-chloro-2-methyl-1-phenyldiazonium borofluoride a vivid red dyeing is obtained with a somewhat yellower hue, the dyestuff having the following formula:

23

30

Example 3.—For printing cotton there is first prepared a grounding bath composed of:

20 grams of 2:3-hydroxynaphthoic acid-4'-chloro-2'-methyl-1'-anilide
40 grams of monopol soap 1:1
500 cc. of boiling water
50 cc. of caustic soda solution of 34° Bé., made up to 1 liter.

The printing paste to be used is prepared from

40 24 grams of 4-chloro-2-methyl-1-phenyldiazonium borofluoride, which is dissolved in 476 grams of water, the solution being thickened with 500 grams of tragacanth (100:1000)
1 liter.

The bleached cotton material is padded with the grounding liquor on a suitable apparatus at a temperature of about 35° C. and dried in the hot flue. It is then printed with the printing color and after drying washed and soaped at boiling temperature.

50 The dyestuff has the following constitution:

55

Example 4.—There is first prepared a grounding bath having the following ingredients:

60 4.5 grams of 2:3-hydroxynaphthoyl-5'-chloro-2'-toluidine (CH3=1)
9 cc. of Turkey red oil of 50 per cent. strength
9 cc. of caustic soda solution of 34° Bé., made up to 1 liter.

65 to which are finally added 4.5 cc. of formaldehyde of 30 per cent. strength.

The material is treated with this grounding liquor for 1/2 hour.

There is then prepared a dye-bath as follows:

2. 37 grams of 2-nitrophenyldiazonium borofluoride are made into a paste with
1. 6 cc. of acetic acid of 50 per cent. strength and some warm water, and the paste is dissolved in 200 cc. of water at 50°-60° C. there are then added about 250 cc. of sodium chloride solution (1:10) and the whole is made up to 1 liter.

The material is dyed for 1/2 hour, then rinsed and soaped at boiling temperature. In this manner a lively bluish-red tint is obtained on the fiber. The dyestuff has the following formula:

Example 5.—There is first prepared a grounding liquor in the manner stated in Example 4.

The dye-bath is also made up like that of Example 4, except that there is substituted for the 2-nitrophenyldiazonium borofluoride the same quantity of 4-nitrophenyldiazonium borofluoride.

The material is rinsed and soaped at a boiling temperature. Thus a bluish-red dyeing is obtained on the fiber. The dyestuff has the following constitution:

Example 6.—There is first prepared a grounding bath with the following ingredients:

7 grams of 2:3-hydroxynaphthoyl-aniline
14 cc. of Turkey red oil of 50 per cent. strength
10.5 cc. of caustic soda solution of 34° Bé., made up to 1 liter.

to which are finally added 7 cc. of formaldehyde of 30 per cent. strength. The material is treated with this grounding liquor for 1/2 hour.

The dye-bath is prepared as described in Example 4, except that there is substituted for the 2-nitrophenyldiazonium borofluoride the same quantity of 3-nitrophenyldiazonium borofluoride.

The material is dyed for 1/2 hour, then rinsed and soaped at boiling temperature. In this manner a lively reddish-orange tint is obtained on the fiber. The dyestuff has the following formula:

73

85

95

100

105

115

120

125

130

Example 7.—There is first prepared a grounding bath with the following ingredients:

5 grams of 2:3-hydroxynaphthoyl-2'-anisidine (OCH₃=1)
 5 10 cc. of Turkey red oil of 50 per cent. strength
 7.5 cc. of caustic soda solution of 34° Bé, made up to 1 liter.

to which are finally added 5 cc. of formaldehyde of 30 per cent. strength. The material is treated with this grounding liquor for 1/2 hour.

The dye-bath is prepared as described in Example 4, except that for 2-nitrophenyldiazonium borofluoride there are substituted 2.75 grams of 2:5-dichloro-4-methylphenyldiazonium borofluoride.

The material is dyed, rinsed and soaped at boiling temperature; a vivid scarlet is obtained on the fiber. The dyestuff has the following formula:

25.

30.

35.

Example 8.—There is first prepared a grounding bath having the following ingredients:

3.5 grams of 2:3-hydroxynaphthoyl-5'-chloro-2'-anisidine (OCH₃=1)
 7 cc. of Turkey red oil of 50 per cent. strength
 8.8 cc. of caustic soda solution of 34° Bé, made up to 1 liter.

to which are finally added 3.5 cc. of formaldehyde of 30 per cent. strength. The material is treated with this grounding liquor for 1/2 hour.

The dye-bath is prepared as described in Example 4, but for the 2-nitrophenyldiazonium borofluoride there are substituted 2.75 grams of 2:3-dichloro-4-methyl-phenyldiazonium borofluoride.

The material is dyed for 1/2 hour, then rinsed and soaped at boiling temperature and thus a dyeing is obtained whose shade resembles Turkey red. The dyestuff has the following formula:

60.

35.

Example 9.—There is first prepared a grounding bath having the following ingredients:

2.5 grams of hydroxynaphthoyl-1'-naphthylamine
 5 cc. of Turkey red oil of 50 per cent. strength
 7.5 cc. of caustic soda solution of 34° Bé, made up to 1 liter.

to which are finally added 2.5 cc. of formaldehyde of 30 per cent. strength. The material is treated with this liquor for 1/2 hour.

The dye-bath is prepared as described in Example 4, but in place of 2-nitrophenyldiazonium borofluoride, 1.91 gram of 4:4'-di(diazonium borofluoride)-diphenylamine is used. The material is dyed for 1/2 hour, then rinsed, acidified with hydrochloric acid, then rinsed cold and hot and soaped at boiling temperature, whereby a black dyeing is obtained. The dyestuff has the following formula:

85

We claim:

1. The process of producing azo dyestuffs on the fiber which comprises treating a hydroxynaphthoic acid arylide on the fiber with a diazonium borofluoride of the following general formula:

105

wherein R stands for an aromatic residue.

2. The process of producing azo dyestuffs on the fiber which comprises treating a hydroxynaphthoic acid arylide on the fiber with a diazonium borofluoride of the following general formula:

110

wherein R stands for a benzene residue which may be substituted by alkyl, O-alkyl, halogen or the nitro group.

3. The process of producing azo dyestuffs on the fiber which comprises treating a hydroxynaphthoic acid arylide on the fiber with a diazonium borofluoride of the following general formula:

125

wherein one X stands for NO₂ and the other X's stand for hydrogen.

4. The process of producing azo dyestuffs

130

on the fiber which comprises treating a hydroxynaphthoic acid arylide on the fiber with a diazonium borofluoride of the following formula:

5. The process of producing an azo dye-stuff on the fiber which comprises treating 2,3-hydroxynaphthoic acid-2'-methyl-1'-anilide on the fiber with the diazonium borofluoride of the following formula:

15 6. The process of producing an azo dye-stuff on the fiber which comprises treating 2,3-hydroxynaphthoic acid-2'-methoxy-1'-anilide on the fiber with the diazonium borofluoride of the following formula:

25 In testimony whereof, we affix our signatures.
